UNITED STATES PATENT OFFICE.

ALBERT E. EDWARDS, OF CALLENDER, IOWA.

DESIGN FOR A CUTTER-GUARD.

SPECIFICATION forming part of Design No. 34,141, dated February 26, 1901.

Application filed January 31, 1901. Serial No. 45,517. Term of patent 7 years.

To all whom it may concern:

Be it known that I, ALBERT E. EDWARDS, a citizen of the United States, residing at Callender, in the county of Webster and State of Iowa, have invented and produced a new and original Design for a Cutter-Guard, of which the following is a specification.

This invention relates to a new and original design for a cutter-guard; and the essential feature resides in the design as illustrated in the accompanying drawing, which illustrates a perspective view of a cutter-guard embodying the design.

The design is characterized by a body 1, having recesses 2 and 3, lateral projections 4, and an enlargement 5. From the said enlargement lower member 6 horizontally projects and has an outer upwardly-deflected portion 7, having an upwardly and rearwardly projecting extension 8 at an angle thereto and

continuous into a top member 9, that has a downward and rearward direction therefrom at an angle of inclination and is terminally disposed over the body 1. From the outer terminal of the portion 7 an arm 10 extends rearwardly at an upward angle of inclination and terminates in a downwardly-curved terminal 11.

Having thus described the invention, what is claimed as new is—

The design for a cutter-guard, as herein shown and described.

In testimony that I claim the foregoing as my own I have hereto affixed my signature in the presence of two witnesses.

ALBERT E. EDWARDS.

Witnesses:

LEVI GUSTAVSON,
J. P. HILSTROM.
